UNITED STATES PATENT OFFICE.

BENJAMIN EGLESTON, OF FRANKLIN, PENNSYLVANIA, ASSIGNEE OF ONE-HALF TO
JOSEPH S. RICHARD, OF FRANKLIN, PENNSYLVANIA.

PAPER-HANGING MACHINE.

1,403,395.

Specification of Letters Patent. Patented Jan. 10, 1922.

Application filed April 1, 1921. Serial No. 457,714.

To all whom it may concern:

Be it known that I, BENJAMIN EGLESTON, a citizen of the United States, residing at Franklin, in the county of Venango and State of Pennsylvania, have invented new and useful Improvements in Paper-Hanging Machines, of which the following is a specification.

This invention relates to a machine for applying sheets of material to surfaces, and more particularly to a machine for hanging wall paper.

One of the main objects of the invention is to provide a machine of the character stated of simple construction and operation which may be produced at comparatively small cost. A further object is to provide a machine by means of which wall paper and similar materials may be quickly and easily applied to surfaces, a suitable adhesive being applied to the paper during passage of the same through the machine. Further objects will appear from the detailed description.

In the drawings:

Figure 1 is a side view of a machine constructed in accordance with my invention.

Figure 2 is a top plan view partly broken away.

Figure 3 is a fragmentary sectional view taken substantially on line 3—3 of Figure 2.

Figure 4 is a section taken substantially on line 4—4 of Figure 2.

Figure 5 is a fragmentary detail section taken substantially on line 5—5 of Figure 1.

The machine includes a base frame 1 of substantially rectangular shape mounted on rollers 2. Four uprights 3 are secured to this base frame and co-operate therewith to support a ladder structure 5. Inner uprights 6 are slidably mounted by means of straps 7 on uprights 3 and co-operate therewith to provide a telescoping structure.

The straps 7 at each side of the machine are connected by a cross bar 8, these bars serving to rotatably support a shaft 9 on each end of which is secured a winding drum 10. This drum receives cables 11 secured at 12 to the guide members or straps 7, these cables being passed over sheaves 13 provided at the upper ends of uprights 3, then under guide pulleys 14 secured on bar 8, the cables being then wound in opposite directions upon drum 10. By turning the shaft 9 in winding or unwinding direction the inner frame consisting of uprights 6

and associated parts may be readily raised or lowered, as desired.

A boxlike casing 15 is suspended between the uprights 6 by means of cables 16 secured at 17 to the casing, these cables being passed over sheaves 18 at the upper ends of uprights 6, then downwardly under guide pulleys 19 secured to the side of the casing, the cables being then wound in opposite directions upon drums 20 secured upon a shaft 65 21 rotatably mounted on the bottom of the casing transversely thereof. By rotating shaft 21 the casing 15 may be raised or lowered in uprights 6, as desired.

A cylindrical paste receiving tube 22 is 70 mounted within casing 15 and is provided in its forward portion with a longitudinally extending slot 23. A worm 24 is rotatably mounted within tube 22, the tube and this worm projecting beyond one side of the 75 casing beneath a paste supply tank 25 secured on the side of the casing, this tank being provided in its bottom wall with an outlet opening controlled by a slide valve 26. The tube 22 is provided with an opening 27 positioned beneath the opening of tank 25 so that by adjusting valve 26 paste may be supplied to the tube as desired. A sprocket wheel 28 is secured on the spindle 29 of worm 24 and is connected by a chain 85 30 to a sprocket wheel 31 secured on the end of spindle 32 of a brush 33 rotatably mounted within casing 15 below and in the plane of tube 22. By rotating worm 24 the paste is fed through the tube and is discharged 90 through slot 23 onto the paper which is led around suitable guide and supporting rollers so as to pass beneath brush 33, the brush being simultaneously rotated and serving to distribute or spread the paste upon the 95 paper.

When using the machine a roll 34 of wall paper is placed upon a rod 35 which is rotatably supported within casing 1 by means of brackets 36. The paper is led from this 100 roll about suitable guide and tensioning rollers 37 supported within the casing so as to pass immediately beneath brush 33. After passing about the rolls 37 the paper passes beneath and in front of a guide roller 38 positioned at the front of the casing and is then led upwardly in advance of a smoothing brush 39. This brush 39 is supported by a rod 40 rockably mounted through the side walls of the casing and provided at one end 110

with a crank 41 which operates between two spaced pins 42 projecting from the side of the casing. One of these pins co-operates with the crank to hold the brush 39 in horizontal position, as illustrated in Figure 1, the other pin co-operating with the crank to hold the brush in vertical position.

When papering the walls of a room the brush 39 is in the position illustrated in Figure 1. The paper is then led from roll 34 about the guide and tension rollers 37 and 38, worm 24 and brush 33 being rotated to apply the paste to the paper, after which the end portion of the paper is applied to the wall surface, casing 15 being then lowered so that brush 34 acts to brush out the paper and apply it to the wall, rollers 37 and 38 and the associated parts co-operating to hold the paper under slight tension during this operation; it being understood that casing 15 is raised to the desired height before commencing the operation described. In applying the paper to the ceiling the brush 39 is moved into vertical position and after the paper has been started the machine is moved across the floor, the paper being applied to the ceiling by the brush during this movement of the machine. In this case the casing 15 is, of course, raised sufficiently to project above the uprights 6.

What I claim is:—

1. In a machine of the character described, a casing, a paste distributing brush rotatably mounted within the casing, means for rotatably supporting a roll of paper within the casing, guide and tensioning rollers rotatably mounted within the casing and disposed to position one run of the paper when passed about said rollers closely adjacent to and below said brush, means for applying the paper to a surface when the casing is moved, and means for rotating said brush and for supplying paste thereto.

2. In a machine of the character described,

a casing, a paste distributing brush rotatably mounted in said casing, a paste receiving tube mounted in the casing above the brush and provided with a discharge opening positioned to discharge paste onto the brush, means for supplying paste to said tube, and means for rotating the brush and for discharging paste from the tube.

3. In a machine of the character described, a casing, a paste distributing brush, means for supporting and guiding a strip of paper in contact with said brush as it is drawn through the casing, a paste supply tube provided with a longitudinally extending opening, means for supplying paste to said tube at one end thereof, and means for feeding the paste longitudinally of the tube and discharging it through said opening onto the brush.

4. In a machine of the character described, a casing, a paste distributing brush, means for supporting and guiding a strip of paper in contact with said brush as it is drawn through the casing, a paste supply tube provided with a longitudinally extending opening and positioned above said brush, means for supplying paste to said tube at one end thereof, and a worm rotatable in the tube for feeding the paste longitudinally thereof and discharging the paste through said opening onto the brush.

5. In a machine of the character described, an outer frame, an inner frame slidably mounted in said outer frame, a casing mounted in the inner frame, means carried by said casing for applying paste to a strip of material drawn through the casing and for applying the strip to a surface during movement of the casing, means for adjusting said casing independently of said frames, and means for raising and lowering the inner frame independently of the outer frame.

In testimony whereof I affix my signature.

BENJAMIN EGLESTON.
